UNITED STATES PATENT OFFICE.

VICTOR LIST AND JACOB KOSAKOFF, OF MOSCOW, RUSSIA, ASSIGNORS OF
ONE-THIRD TO GEORG ADOLF LIST, OF SAME PLACE.

PETROLEUM-MOTOR.

SPECIFICATION forming part of Letters Patent No. 378,328, dated February 21, 1888.

Application filed October 29, 1887. Serial No. 253,708. (No model.)

To all whom it may concern:

Be it known that we, VICTOR LIST, engineer, and JACOB KOSAKOFF, mechanic, both subjects of the Emperor of Russia, residing at 5 Moscow, in the Russian Empire, have invented new and useful Improvements in Petroleum-Motors, whereof the following is a specification.

Our invention relates to engines in which 10 motive power is produced by the explosive combustion of a mixture of petroleum or other liquid hydrocarbon and air; and the improvements consist in the means employed for heating the air by the heat given off from the explosion - chamber of the power-cylinder, for 15 mixing the same with dispersed petroleum, and for exposing the mixture to the heat of the exhaust-gases in view of evaporating the petroleum.

Moreover, the invention comprises an igniting device having an expandible chamber for the transmitting-flame by which the explosive mixture is lighted.

An engine of this kind involving our improvements is shown on the annexed three sheets of drawings.

Figure 1 is a sectional plan; Fig. 2, an end view with section through the explosion-chamber of the power-cylinder and parts connected thereto; 30 Fig. 3, a transverse section through the front end of the power-cylinder and the rear end of the air-pump; Fig. 4, a longitudinal section along the center line of the power-cylinder; Fig. 5, a transverse section through the igniting device, drawn to a larger scale; Fig. 6, a section on line 1 2, and Fig. 7 a section on line 3 4 of Fig. 5; and Fig. 8, a sectional plan of a modified construction of the igniting device.

A is a pump serving for the supply of compressed air, and B the power-cylinder, having at its end the explosion-chamber C. The pistons of the pump and the cylinder are connected by rods to the respective cranks G and H of a common crank-shaft, the said cranks 45 being placed parallel to each other on the same side of the shaft.

b, Fig. 2, is the valve for the admission of explosive mixture to the cylinder B; K, the exhaust-valve, and X a shaft driven by the 50 crank - shaft through the medium of bevel-wheels, and carrying cam for operating the said

valves and the igniting device, the valve b being opened by the action of the cam x on the roller v of the lever v and closed by the spring w, while the valve K is opened by the cam r', 55 acting thereon by means of the rod q', with roller s', and the lever t, and closed by the spring p'.

The petroleum to be supplied to the engine is drawn by a pump, P, through the suction- 60 pipe g from a reservoir (not shown in the drawings) and discharged through the pipe i, and in this pipe a cock, R, is inserted, the plug whereof is so perforated and connected to the governor S that when the speed of the 65 engine becomes too great a part or the whole quantity of the petroleum will pass back into the suction-pipe g. The said cock is, however, not shown in detail, as it does not form any part of the invention which we claim. 70

The air-pump A and the cylinder B are both inclosed in jackets, and the inside space of the cylinder-jacket is divided by longitudinal partition-walls, forming a channel, e, which communicates at one end by a pipe, d, with the pump, 75 and at the other end with a jacket, C, surrounding the explosion-chamber C, with a narrow intervening space, f. To the jacket C is attached the petroleum-evaporator, composed of two metallic surfaces, forming a narrow but 80 extended passage, the said surfaces consisting, after the construction shown by the drawings, in the walls of the vessel D, preferably made of copper, and the walls of the cylindrical body E, hung into the said vessel D, and which 85 leaves between itself and the latter the narrow space m. The body E, which has a central channel, h, is fixed to a pipe, k, branching off from the jacket C, so that a communication is produced through the said channel and the 90 pipe k between the space f of the jacket and the space m of the evaporator. The vessel D is bolted to a tubular branch, l, of the jacket C, the said branch surrounding the branch pipe k with an intervening space, n, which 95 communicates by means of a channel, p, with the valve - chamber F, leading to the explosion-chamber C. The vessel D is inclosed in a casting, M, connected to the exhaust-pipe L, so that the exhaust-gases will pass around the 100 same and heat it. Into the branch pipe k is inserted the nozzle of the discharge-pipe i of

the petroleum-pump P, the said nozzle being so arranged that the petroleum will be projected against the outer surface of the explosion-chamber, or any other wall, and thereby 5 divided into spray.

The air is drawn in by the piston of the pump A through the valve-orifice a, and after having been compressed during the return-stroke of the piston to about one-half of its 10 original volume it is driven past the valve c and through the pipe d into the channel e, where it is slightly heated. Thereupon it flows through the space f, where it becomes heated to a high degree. On its further course 15 through the pipe h the air meets with the petroleum spray present therein, and in dispersing the same still more mixes therewith and carries it along through the channel h into the space m, where the petroleum is evaporated 20 upon the heated walls of the vessel D. At the time the valve b is open the mixture of air and petroleum vapor thus produced then passes through the space n, the channel p, and the valve-chamber F into the cylinder B, where it joins 25 with the residual combustion-gases. In consequence of the pistons moving in the same direction, a further compression of the air still passing over from the pump A of the combustion-gases having remained in the cylinder 30 and of the explosive mixture already formed then takes place until the pistons have arrived at the end of their return-stroke. Soon after 35 this the mixture is ignited.

Previous to the starting of the engine the vessel D must be heated by a petroleum-lamp, N. After the engine has been put in motion and the exhaust-gases have become hot enough to be alone capable to evaporate the petroleum, the lamp is extinguished, and the bottom 40 of the vessel D is protected from cooling by a slide introduced into the groove q.

In view of reducing the counter-pressure in the cylinder when, at the starting of the engine, the fly-wheel is turned by hand, the shaft 45 X is provided with a cam, r², longer in peripheral direction than the aforesaid cam r', and arranged to act on a roller, s', rotating about a pin on the rod q', and which may be temporarily pushed into the path of the cam 50 r², the exhaust-valve being thereby kept open for a greater length of time than by the cam r'.

The igniting device is seen to best advantage from Figs. 5, 6, and 7. It consists of the slide a', having a cylindrical boring, the 55 stationary piston b', inserted thereinto, the plate c', screwed to the valve-chamber F, and having the aperture l' leading to the said chamber, and of the cover d', with aperture h', the cover being pressed against the slide and the 60 latter against the plate c' by four springs, e', (only one appearing in the drawings.) The bottom of the boring of the slide and the end of the piston b' have both semi-conical excavations, forming together, when both parts are 65 in contact with each other, the conical igniting-chamber f'. When the slide is in its nor-

mal position, in which it is kept by the cam r, Fig. 1, acting on the same by means of the roller s, the rod y, and the lever z z', the said chamber f' communicates at its base with the 70 aperture h', in front of which is placed the permanent igniting-flame i'. From the apex of the chamber f' a narrow channel, k', leads to the edge of the aperture l', being in the drawings on the left-hand side. Besides, the slide 75 has the aperture m'. If with this arrangement compressed explosive mixture enters into the chamber F, a small portion thereof passes through the channel k' into the chamber f', expands within the same, ignites at the flame 80 i', and continues to burn inside of the chamber f', the flame thus produced being the transmitting-flame. At the moment the ignition of the contents of the cylinder is to take place 85 the cam r abandons the roller s, and the spring u, thus becoming free to act, draws the slide a' in the direction away from the piston b'—i. e., in Figs. 6 and 7 to the right. The aperture h' is thereby closed, and simultaneously the chamber f' is expanded, in consequence 90 whereof the transmitting-flame retreats toward the narrower end of the chamber. As soon as the slide has advanced far enough that communication is established between the aperture l' and the chamber f' by means of the aperture m', the explosive mixture contained in 95 the valve-chamber F and in the cylinder ignites through the said apertures at the transmitting-flame. In order that the feeding of this flame may not cease too soon, the small 100 channel n' is provided for, which entertains the communication between the aperture l' and the channel k' for a short time after the latter has been covered by passing under the full portion of the plate c', being in the drawings 105 on the right-hand side of the aperture l'. At the required moment the slide a' is returned to its normal position by means of the cam r. 110 In the modified construction shown by Fig. 8 the conical chamber f' is arranged entirely 110 in the slide a', and the piston b' is so adjusted that when the slide is in its normal position a space, t', is left between the bottom of the boring in the slide and the end of the piston b', the said space communicating by the aperture m' and a narrow channel, v', with the aperture l', and by the wider channel, u', with the apex of the chamber f'. While in the 115 said chamber the transmitting-flame is produced, the space t' fills through the channel v' 120 and the aperture m' with explosive mixture. The slide being then moved as described above, the flame burning in the wider portion of the chamber f' will, on account of the expansion 125 of the space t', be drawn through the channel u' into the said space. The explosive mixture contained therein ignites, and immediately after transmits ignition to the mixture in the chamber F and the cylinder. Before the engine is started the slide requires to be heated 130 by means of the flame o'; but in order to keep the surfaces of the slide and of the plate c' suf-

ficiently cool there are cut into the said surfaces channels, through which water is caused to flow. These channels are omitted in the drawings. For adjusting the width of the 5 channel k' the same may be provided with a regulating-screw.

We claim as our invention—

1. In a petroleum-motor, the combination, with the air-pump A, cylinder B, explosion-chamber C, and exhaust-pipe L, of the jacket C', surrounding the chamber C, means of communication between the said jacket and the pump A, a petroleum-evaporator composed of two metallic surfaces having between them 15 a narrow space, m , two channels connecting the space m with the jacket C' and the chamber C, the casing M, communicating with the exhaust-pipe L and inclosing the evaporator, and the petroleum-supply pipe i , substantially 20 as and for the purpose described.

2. In a petroleum-motor, the combination, with the explosion-chamber C, of an igniting device comprising the plate c' , the cover d' ,

the tubular slide a' , and means for operating said slide, and the stationary piston b' , fitting 25 or located in said slide, these parts being constructed and arranged for joint operation, substantially as and for the purposes hereinbefore set forth.

3. In a petroleum-motor, the combination, 30 with the explosion chamber C, of an igniting device comprising the plate c' , with aperture l' , the cover d' , with aperture h' , the slide a' , having a cylindrical boring, an aperture, m' , and a channel, k' , the stationary piston b' , 35 located in the said boring, the conical igniting-chamber f' , and means for operating the slide, substantially as and for the purpose specified.

In testimony whereof we have hereunto set our hands in the presence of two subscribing 40 witnesses.

VICTOR LIST.
JACOB KOSAKOFF.
